UNITED STATES PATENT OFFICE.

THOMAS N. SOLOMON AND HARRY D. SOLOMON, OF DETROIT, MICHIGAN.

AIR-DUMPING BALLAST-CAR.

1,297,924.

Specification of Letters Patent. Patented Mar. 18, 1919.

Application filed July 25, 1918. Serial No. 246,788.

To all whom it may concern:

Be it known that we, THOMAS N. SOLOMON and HARRY D. SOLOMON, citizens of the United States, residing at Detroit, in the county of Wayne and State of Michigan, have invented certain new and useful Improvements in Air-Dumping Ballast-Cars, of which the following is a specification, reference being had therein to the accompanying drawing.

This invention relates to ballast cars and has for its object the production of a simple and efficient means for quickly unloading a train load of ballast whereby all of the cars may be emptied simultaneously.

Another object of this invention is the production of a simple and efficient means for controlling the swinging of the dumping doors both to an open and a closed position.

With these and other objects in view this invention consists of certain novel constructions, combinations and arrangements of parts as will be hereinafter fully described and claimed.

25 In the drawings:—

Fig. 1 is a side elevation of the car.

Fig. 2 is a top plan view thereof being partly broken away.

Fig. 3 is a section taken on line 3—3 of Fig. 1.

Fig. 4 is a section taken on line 4—4 of Fig. 3.

Fig. 5 is a section taken on line 5—5 of Fig. 3.

35 Fig. 6 is a section taken on line 6—6 of Fig. 5.

Fig. 7 is a sectional perspective view showing the manner of hinging the dumping doors upon the frame of the car.

40 Fig. 8 is a side elevation of a portion of the frame of the car dumping doors, supporting bars being shown in section.

Fig. 9 is a section taken on line 9—9 of Fig. 8.

45 Fig. 10 is an enlarged vertical section through the lower end of the cylinder.

Fig. 11 is an enlarged vertical section through the upper end of the cylinder.

Fig. 12 is a transverse section through the 50 bearing portion of one of the brackets supporting the door controlling shaf.

Fig. 13 is a bottom plan view of the sliding door operating head.

55 Fig. 14 is a vertical section through the valve casing used in connection with the present invention.

Fig. 15 is a section taken on line 15—15 of Fig. 14.

By referring to the drawings it will be seen that 1 designates the frame of the car 60 which is provided with a centrally located longitudinally extending inverted substantially V-shaped rib 2, constituting the main floor of the car. A longitudinally extending side plate 3 is secured near each lower side 65 edge of said rib 2 by having the flange portion 4 thereof fixed securely to the under face of the rib 2. Each side plate 3 is provided with a laterally extending flange 5 to which flange is secured the transversely extending angle-irons or bars 6. These bars 6 carry brackets 7 which brackets 7 are provided with clamping members 8 formed of a plurality of sections, firmly held together by means of suitable bolts 9.

75 This sectional clamp 8 fits around a journal portion 10 carried by the door controlling or operating shaft 11, the shaft 11 being square in cross section.

A door 12 is carried below each side edge 80 of the rib 2 and is adapted to normally close the discharge opening formed along the side of the car 1. Each door 12 comprises an elongated plate which is supported upon the transversely extending angle bars 14. These 85 angle bars 14 extend through the apertures 15 formed in the side plates 3 and are pivotally mounted upon the supporting brackets or ears 16 which are carried by the side plates 3. The inner ends of these angle bars 90 14 project inwardly toward the center of the car and are adapted to constitute a means for balancing the doors 12 and also for limiting the swing of the doors, should the inner ends of the angle bars 14 come in contact with the under face of the center rib 2.

The door controlling or operating shaft 11 carries an arm 17 which is connected to an angle plate 18, this plate 18 being connected to the outer end of one of the bars 14, as 100 shown clearly in Fig. 3. This angle plate is pivotally connected to the arm 17 by means of a pivot pin 19 and it will be seen that the flange portion 20 of the plate 18 will constitute a means for limiting the swing of the 105 plate 18 in one direction or while the door 12 is being swung to a closed position. As the door is being swung to an open position, this plate 18 may easily swing upwardly with respect to the arm 17.

110 Each shaft 11 also carries a swinging arm 21 which is connected to a link 22. This

link 22 is pivotally connected to the lower end of the hanger arm 23, the hanger arm 23 being pivotally connected upon the supporting plates 24. These supporting plates 5 24 are secured to channel plates 25 carried by the longitudinally extending irons 26 carried by the body of the car. Each hanger arm 23 carries a link 27 which link is in turn connected to a depending eye 28 carried 10 by the operating head 29. This head 29 is provided with projecting lips 30 upon each side thereof, which lips 30 fit between the guide bars 31 and are secured to the longitudinally extending channel irons 26 as 15 shown clearly in Fig. 3 of the drawings.

A piston rod 32 is carried by the head 29 and this piston rod carries a collar 33 and a collar 34, the collars 33 and 34 being spaced from each other to permit the piston rod 32 20 to have a suitable limited movement through the head 29 without moving the head. The lower end of this piston rod 32 carries a frame 35 which frame 35 is provided with a plurality of rollers 36 and these rollers 36 25 engage the beveled faces 37 of the latching bars 38. These latching bars or arms 38 are provided with notches 39 formed therein which notches are adapted to fit over the side edges 40 of the head 29. It will be seen 30 therefore that as the plunger rod 32 is moved downwardly, the rollers 36 will engage the beveled faces 37 and force the arms 38 outwardly thereby releasing the notches 39 from engagement with the head 29 as will 35 be obvious by considering the drawings. As soon as the arms 38 are released from the head 29, the collar 34 will engage the head 29 and permit the plunger rod 32 to move upwardly, the weight of the ballast within 40 the car forcing the door 12 downwardly and causing the arms 17 and 21 to swing and thereby pushing the links 22 and 27 of the hanger arm 23 inwardly.

When it is desired to close the doors 12, 45 the plunger rod 32 is forced outwardly by means of the structure hereinafter described thereby forcing the links 27 and 22 outwardly and swinging the hanger arms 23 as well as the arms 21 and 17 thereby swinging 50 the doors 12 to a closed position. As the plunger rod 32 is moved or forced downwardly the head 29 will fit into the notches 39 of the arms 38 due to the fact that these arms 38 are forced against arms 29 by 55 means of the spring pressed flanges 41 which are mounted within the casing 42 suspended below the plates 43 carried by the longitudinally extending channel irons 26. These flanges 41 are provided with notches 60 44 within which notches the arms 38 fit.

By considering Fig. 6 it will be seen that the arms 38 are pivotally mounted upon the supporting brackets 45. A cylinder 46 is mounted below the rib 2 and upon the longitudinally extending channel iron 26 and

this cylinder 46 carries a plunger head 47 carried by the plunger rod 32. A cylinder head 48 is secured to the upper end of the cylinder 46 and the cylinder 46 is provided with a port 49 near this upper end carrying 70 a ball valve 50 which is adapted to prevent air from passing down through the port 49 and at the same time permit air to pass upwardly through the port 49. The port 49 is provided with a discharge aperture 51 near 75 the top of the cylinder and an intake aperture 52 so as to permit the air to be forced from under the plunger head 47 and above the plunger head or piston head as soon as the plunger rod starts in its downward 80 movement.

The cylinder 46 has a communicating pipe 53 communicating with the top plate 48 of the cylinder and this communicating pipe 53 as shown clearly in Fig. 2 communicates with the auxiliary or reservoir 54. This reservoir 54 is also connected to a pipe 55 which pipe communicates with one end of the valve casing, the opposite end of the valve casing 56 communicating with a pipe 57 connected to a train pipe 58. The valve casing 55 carries a pipe 59 which pipe 59 communicates with the cylinder 47, as shown in Figs. 4 and 14 and this valve casing 56 carries a sliding valve 60 which sliding valve 95 60 is provided with a circular passage 61 around the outer face thereof and near its lower end. As the valve 60 is raised to cause the exhaust port 62 of the casing 56 and the inlet port 63 to register with the channel 100 or groove 61, it will be seen that the air may readily be passed out from the cylinder 46 through the pipes 59, port 63, channel 61 and port 62. When the air is turned into the train pipe 58, the pressure forces the 105 valve piston 60 to the opposite end of the valve thereby closing the port or channel 61. When the air is released from the train pipe the air pressure from the auxiliary being 110 greater, the valve piston is forced to the opposite end of the valve casing thereby opening the port 61 and permitting the air to escape into the atmosphere. When the piston has traveled down a full stroke, the air from the auxiliary may also escape through 115 this port 62 as the piston 60 opens the port 62.

As shown in Fig. 10 the piston rod 32 works through a packing 64 which packing supports or carries a leather cup washer 120 65, which fits snugly around the piston rod 32.

From the foregoing description it will be seen that a very simple and efficient means has been produced for causing the car to be dumped merely by the action of the air passing from the train pipe as above described, the doors being released thereby, and after the material has been dumped from the car, the doors may be swung to a 130

closed position at the will of the person actuating the train pipe line.

What is claimed is:—

1. A dumping car of the class described comprising a body, a centrally located inclined rib carried by said body, a door mounted upon said body upon each side of said rib, transversely extending angle bars secured to said door and projecting under said rib for counterbalancing said door, lever means engaging said door for swinging the same, means for swinging said lever means, and means for locking said lever means against swinging movement.
2. A dumping car of the class described comprising a body, a centrally located rib carried by said body, a door mounted upon each side of said body adjacent the lower edge of said rib, transversely extending angle-bars connected to said door and projecting under said rib, means for swinging said doors, side plates supporting said doors, and said side plates provided with apertures for receiving said transversely extending bars.
3. A car of the class described comprising a body, dumping doors hingedly secured thereto, a door controlling shaft, arms connected to said shaft and engaging said doors for swinging said doors as said shaft is rotated, link means connected to said shaft, a hanger arm carried by said body, and means for locking said hanger arm against swinging movement.
4. A car of the class described comprising a body, dumping doors hingedly secured thereto, a door controlling shaft, arms connected to said shaft and engaging said doors for swinging said doors as said shaft is rotated, link means connected to said shaft, a hanger arm carried by said body, a vertically movable operating head, and a link connected to said vertically movable head and to said hanger arm for swinging said doors to a closed position as said head is moved vertically.
5. A car of the class described comprising a body, dumping doors hingedly secured thereto, a door controlling shaft, arms connected to said shaft and engaging said doors for swinging said doors as said shaft is rotated, link means connected to said shaft, a hanger arm carried by said body, a vertically movable operating head, and a link connected to said vertically movable head and to said hanger arm for swinging said doors to a closed position as said head is moved vertically, and means for locking said head against vertical movement.
6. A dumping car of the class described comprising a body, dumping doors, a cylinder casing, a plunger working in said cylinder casing, means for locking said plunger against vertical movement, and means for releasing said locking means for permitting said doors to automatically swing to an open position.
7. A car of the class described comprising a body, doors carried by said body, a plunger, a head carried by said plunger, means connecting said head to said doors for swinging said doors to a closed position as said head is moved downwardly, and means for normally locking said head against longitudinal movement.
8. A car of the class described comprising a body, dumping doors carried thereby, a piston rod, a head carried by said piston rod, means connecting said piston rod with said doors, means for reciprocating said piston, rollers carried by the lower end of said piston, latching bars, a head carried by said piston rod, said latching bars provided with notches formed therein for engaging said head and holding the same in a locked position, and rollers carried by said piston rod, for forcing the notches of said doors out of engagement with said head for permitting said head to freely move to a vertical position.
9. A car of the class described comprising a body, doors carried thereby, a cylinder, a piston rod for actuating said doors mounted within said cylinder, a valve casing, a train pipe, said valve casing connected to said train pipe, a valve slidably mounted within said valve casing and provided with means for permitting said power to be drawn from said cylinder, and a reservoir connected to said cylinder for feeding power to the said cylinder.

In testimony whereof we hereunto affix our signatures.

THOMAS N. SOLOMON.
HARRY D. SOLOMON.
